PIN RESETTING UNIT FOR BOWLING GAMES

Joe H. Warner, Chicago, Ill., assignor, by mesne assignments, to R. W. Hood, Chicago, Ill.

Original application August 9, 1939, Serial No. 289,153. Divided and this application November 1, 1939, Serial No. 302,275

3 Claims. (Cl. 273—44)

This invention relates to amusement apparatus and is a division of my copending application, Serial No. 289,153, filed August 9, 1939, which has matured into Patent No. 2,181,984.

5 The principal object of the invention is the provision of pin setting and score control means for use in a miniature bowling game.

10 A more particular object is the provision of pin setting means including a vertical support and a plurality of bowling pins each suspended from the support by an overhead cable, each cable having attached to the free end thereof a vertically movable counterweight tending to raise the corresponding pin from the bowling alley.

15 Another object is the provision of improved magnetic means for attracting the several pins in lowered position in the alley, the pins being automatically raised by action of their counterweights when the magnetic attraction is broken by impact of the bowling ball with the pin.

20 Another object is the provision of score control means including a plurality of switches each mounted to be operated by one of the counterweight members in lowering movement to hoist 25 the corresponding pin when the latter is struck.

Still another object is the provision of resetting means including a common vertically movable resetting bar underlying all of the counterweights and reciprocated by a motor to lift the 30 counterweights and lower the pins into the alley for seizure by the magnetic means.

Other objects, advantages and novel aspects of the invention relate to certain details of construction, as well as the functional relationship of the 35 various parts of the resetting structure, including the vertical support, pin racking device and shield, means for supporting the switches, and the construction and operation of the common resetting means, all of which will become more apparent as the following description proceeds in view of the drawing, in which:

Fig. 1 is a perspective of the pin setting structure including a fragment of the bowling alley;

Fig. 2 is a vertical section through one of the 45 counterweight and switch devices viewed along line 2—2 of Fig. 1;

Fig. 3 is a vertical section through one of the pins and magnetic attracting devices, drawn to enlarged scale, and as viewed along line 3—3 50 in Fig. 1.

The pin resetting unit, as shown in Fig. 1, includes a support including a pair of uprights or posts 10 secured at their lower ends to a horizontal panel member 11 and at their upper ends, 55 as at 12, to a laterally projecting shield member 13 which has a racking web 14 formed integrally thereof and provided with a plurality of triangularly arranged pin receiving holes 15 into which the several bowling pins fit when in raised 60 condition, the purpose of the racking member

being to dispose the pins in their proper spaced relationship and pattern when in raised condition so that they will automatically lower into approximately proper position

5 At the top of the laterally projecting shield member 13 are a plurality of rod members 17 each having formed therein a plurality of circumferential grooves 17a constituting guideways for cords or cables 18 each attached to one of the pins 16. The free end portions of the cables 10 are each led downwardly for connection in a sleeve portion 19, threaded as at 20, onto the upper end portion of a counterweight rod 21, the several rods each being of a weight adequate to raise the corresponding pin.

15 The several counterweight rods 21 are supported for vertical movement in alignment with their corresponding cables by a cross rod 22 secured to the posts 10 and by a horizontally extending switch mounting shelf 23 also fixed on 20 the posts 10.

At their lower ends each of the counterweight rods rests on a common crossbar 24 which is formed as an offset of a vertical apron 25 slidably mounted as at 26 on the posts 10. Thus, 25 by moving the apron 25 or the common crossbar portion 24 vertically, all of the counterweight rods 21 will be raised with a consequent lowering of each of the corresponding pins.

Means for raising the several counterweight 30 rods as aforesaid to lower, and hence reset, the pins, includes a motor 30 mounted on the panel portion 11 and provided with an eccentric 31 having a stud portion 32 (Fig. 2) which underlies the common resetting or crossbar portion 24 of 35 the apron 25 and is adequate to elevate the latter when the motor is energized. It may be observed also that the eccentric 31 is provided with certain commutating contact portions 31a cooperating with wiper contacts 33 for connection in 40 a control circuit related to the automatic resetting operation and ball elevating means, not shown in this application, but disclosed in the aforesaid copending application.

It may be further observed that the shelf portion 23 provides a support as at 34 for a vertically reciprocable ball elevating tube 35 which is adapted to be actuated by a mechanism (not shown) to elevate a bowling ball into position for gravitation down a ball return runway 36 on 50 the bowling alley 37, the ball subsequently being propelled at the tenpins in their lowered condition in an effort to strike as many of the pins as possible and effect elevation of the same from the alley by operation of the counterweights 21. 55

Means for releasably securing the several 60 bowling pins in the alley includes the provision of a corresponding number of permanent magnets 40 (Fig. 3) which are preferably made from rod stock having suitable physical properties for 60

permanent magnetization, short pieces of the stock being cut to provide the magnets 40, which are slotted, as at 41, to provide pole pieces 42, the magnets being fitted into holes in the alley 37 with the pole pieces 42 flush with the upper surface thereof. In the bottom of each pin 16, there is formed a bore 43 in which the knotted end portion of the cable is disposed and into which is threaded a magnetic screw 44, preferably of the flat-head variety, with the head portion 45 fitted flush with the bottom of the pin so that the pin may rest firmly on the alley with the head portion 45 attracted to bridge the pole pieces 42 of the corresponding magnet. 10 15 20 25 30 35

Score control means operably controlled by the counterweight members includes the provision of a plurality of switches 50 mounted on the shelf portion 23 and each having an operating spring or extension 51 disposed adjacent one of the counterweight rods 21 for engagement by a collar portion 21a on the rod when the latter is in lowered condition whereby the operating member or spring 51 is moved to dispose the switch in a normal condition. It will be observed that the switches include a plurality of contact springs, some of which are in closed circuit relationship when the switch is in normal condition, and other contacts of which are closed by movement of the operating member or spring 51 when the corresponding counterweight rod is raised. The switches 50 are intended to be connected in a score control circuit (not shown) fully described in the aforesaid copending application. 40 45 50 55

In the operation of the improved pin racking and setting means, it may be assumed that all of the pins save one have been struck and lifted into the full line position beneath the shield or hood 13, as illustrated in Fig. 1, each pin fitting into its corresponding racking hole 15. In this condition, the corresponding counterweight rods 21 will be lowered with their lower ends resting on the common resetting or crossbar 24. Since one of the pins 16a has remained in lowered position, the corresponding rod remains in raised position with its lower end above the resetting bar 24, as indicated in dotted lines (Fig. 1).

Assuming that the pin 16a, which remains on the alley in Fig. 1, were to be struck by the bowling ball, the momentary dislodgement thereof would separate the head portion 45 of the magnetic screw in the bottom thereof sufficiently from attracted engagement with the pole pieces 42 of the corresponding magnet, to enable the corresponding counterweight rod to lift the pin free from the attraction of the magnet. 50 55

Whether or not all of the pins have been lifted from the alley 37, resetting may be effected by energizing the motor 30 (circuit connections for which constitute separate matters of invention not described or claimed in this application) to start the eccentric 31 upon its cycle of operation, which is controlled by cooperation of the commutator contacts 31a and wipers 33 as an incident in the operation of the aforesaid control circuit, so that the eccentric will make one revolution, thus raising the common resetting bar 24 and returning the same to its normally lowered condition shown in Fig. 1. This movement of the 60 65 70 resetting bar will raise such of the counterweight rods as are lowered, thus lowering the corre-

sponding pins onto the alley, the pins being attracted and held in proper position by their corresponding magnets 40. When the rods 21 are in lowered condition, the corresponding collar portions 21a thereon engage and depress the operating spring extensions 51 of the corresponding score control switches for the purpose heretofore mentioned, such springs being permitted to restore to normal condition when the rods are restored to raised condition by action of the resetting bar as aforesaid. 10 15 20

The various advantages and objects of the invention may be accomplished by modifications of the particular embodiment specifically described herein, and it is intended that the appended claims shall include all equivalent arrangements fairly coming within their call. 25

Having thus described my invention, what I claim as new and desire to protect by Letters Patent is:

1. In a bowling game, the combination with a pin setting mechanism including a plurality of vertically reciprocable counterweight rods each connected by overhead cable means to a bowling pin which is lowered on to an alley when the corresponding rod is in raised position, of score control means including a horizontal platform extending opposite said rods, and a plurality of leaf spring switches on said platform and adapted for connection in a score control circuit, said switches each having an elongated operating member projecting in a radial direction toward one of said rods, and means on said rods operatively engageable with the operating member of the corresponding switch responsive to axial movement of the rods. 30 35 40

2. In a bowling game, in combination, pin setting and score control means including an upright rack adapted for mounting adjacent a bowling alley, a plurality of counterweight rods mounted in side by side alignment for vertical movement in said rack and each connected by overhead cable means to a tenpin adapted to be lowered and releasably held on said alley responsive to upward movement of the corresponding rod, a common resetting member underlying all of said rods and means for effecting reciprocation of said resetting member for the purpose of lowering said tenpins on to said alley, a horizontal platform, extending opposite said rods, switch means on said platform and means including a lateral projection on one or more of said rods for actuating said switch means responsive to axial displacement of the rod. 45 50 55

3. In a device of the class described, pin setting means including an upstanding support, a plurality of elongated counterweight rods mounted in side by side relation on said support for vertical reciprocation, each of said rods being adapted to be connected by overhead cable means with a bowling pin adapted to be lowered onto an alley and releasably held on said alley responsive to upward movement of the corresponding rod, means adjustable in a direction axially of each rod for connecting the same with said cable means of a corresponding bowling pin, and means for raising any of said rods from lowered to raised position for the purpose aforesaid. 60 65 70 75
